ABSTRACT: A snap action electric switch includes a housing having a pair of stops in spaced relation and forming first and second electrical contacts, and a switch actuating member displaceably mounted in the housing. A third electrical contact forms a fulcrum for an intermediate portion of a two arm electrically conductive angle lever which is engaged by the actuating member. An electrically conductive contact arm has one end bearing pivotally on one arm of the lever and its other free end movable between the first and second contacts. A tension spring has one end connected to a first suspension point on the contact arm and its opposite end connected to a second and fixed suspension point on the housing beyond the fulcrum and beyond the other arm of the lever. The line of action of the tension spring always remains in spaced lateral relation to the same side of the fulcrum in all positions of the switch. A pair of abutments on the other arm of the lever embrace the tension spring between the lever fulcrum and the fixed suspension point and deflect the tension spring to one side of the straight line interconnecting the first and second suspension points. The tension spring, acting through the contact arm, exerts a torque tending to pivot the lever in one direction about the fulcrum, and the deflection of the tension spring by the abutments exerts a torque tending to pivot the lever in the opposite direction about the fulcrum. The two torques, acting in opposite directions, result in only a small force on the actuating member being necessary to snap the contact arm from a rest position to an actuated position. In the actuated position, the abutments deflect the tension spring in the opposite direction relative to the straight line connecting the first and second suspension points, so that the spring exerts a restoring force on the contact arm. Preferably the contact arm and the lever arm upon which it bears are forked to provide for passage of the tension spring between the arms of the forks.

SNAP ACTION ELECTRIC SWITCH

BACKGROUND OF THE INVENTION

The present invention is directed to that type of snap action electric switch including a contact arm pivotally displaceable between two stops and which is biased, by an extension spring, into bearing engagement on a means adjustable as a function of the switch-actuating member, this means being mounted at a point outside of any possible direction of action of the spring and being returned to its rest position by the extension spring, after adjustment thereof as a function of the switch-actuating member.

In snap action switches of this type, the fixed contact engaged by the contact arm in the actuated position of the latter and the rest contact engaged by the contact arm in its rest position are frequently spaced quite considerably from each other. It is desirable to reduce the distance through which the free end of the contact arm has to move, in disengaging one contact and engaging the other contact, to increase the sensitivity of the switch, as for operation as a feeler switch.

For this purpose, it has been proposed to provide, in addition to the adjustable means mounting the pivotal contact arm, another means adjustable outside of any possible direction of action of the extension or tension spring as a function of the actuating member. This other adjustable means deflects the second point of action of the extension spring in the sense of accelerating the overriding of the dead center position, transversely or obliquely to the direction of action of the tension spring. The first point of action of the tension spring is, of course, on the contact arm.

The resulting deflection forces acting in opposite directions at opposite ends of the extension spring then effect a rapid change of the inclination of the spring, with respect to the contact arm. Conversely, the spring force acts on the switching system at two adjustable means. Depending on the design of the system, the torques produced at the adjustable means, which may be, for example, angle levers, may be codirectional or may be counterdirectional, and thus may add to or subtract from each other to attain automatic resetting of the switching system. Especially when the torques act counter to each other, appreciable advantages result because, for example with the use of a strong tension spring, which has an advantageous effect on the contact force, only relatively small actuating forces are necessary.

It is furthermore known, in a snap action electric switch including a switching system constructed in the manner of a toggle joint, to provide, on a fixed intermediate lever, a tappet or abutment for the tension spring which connects a rigid contact arm with a fixed suspension point through the tappet. However, since in this known arrangement the intermediate lever is not mounted outside of any possible direction of action of the tension spring, the tappet is necessary, in this case, to make possible an automatic resetting of the switching system.

SUMMARY OF THE INVENTION

This invention relates to snap action electric switches and, more particularly, to a snap action electric switch of the general type mentioned above but in which the results attainable with prior art constructions are attained using only one means adjustable as a function of the actuating member.

The present invention utilizes the concept of adjusting the tension spring at two-spaced points of the switching system, with utilization of the reaction forces. To this end, an intermediate lever, serving as a single adjustable means, is arranged substantially parallel to the unilaterally suspended tension spring having its ends fixed in a known manner. The tension spring extends substantially centrally of the longitudinal extent of the lever. The intermediate lever carries, at its end or arm projecting toward the fixed suspension point of the tension spring, abutment means or a tappet for the tension spring and acting on the latter at a point located between the spring suspension points and in a direction substantially transverse to the line connecting the two suspension points of the spring.

An object of the present invention is to provide an improved and simplified snap action electric switch.

Another object of the invention is to provide an improved and simplified snap action electric switch including only a single means or member adjustable as a function of a switch-actuating member.

A further object of the invention is to provide such a snap action electric switch in which such single means comprises an intermediate lever extending substantially parallel to a tension spring having one end connected at a fixed point of a switch housing and its opposite end connected to a contact arm and biasing this contact arm into pivotal bearing engagement with the intermediate lever.

Yet another object of the invention is to provide such a snap action switch in which the intermediate lever is pivoted in the housing intermediate its ends, with its arm extending toward the fixed suspension point of the spring carrying abutment means engageable with the tension spring at a point intermediate the ends of the latter and acting on the spring in a direction substantially transversely of the line connecting the two suspension points of the spring.

A further object of the invention is to provide such a snap action switch in which the abutment means acts on both sides of the spring during pivoting of the intermediate lever.

Still another object of the invention is to provide such a snap action switch in which the abutment means embraces the contact spring.

A further object of the invention is to provide such a snap action electric switch in which the abutment means acts on only one side of the spring.

BRIEF DESCRIPTION OF THE DRAWINGS

For an understanding of the principles of the invention, reference is made to the following description of a typical embodiment thereof as illustrated in the accompanying drawings.

In the Drawings:

FIG. 1 is a side elevation view of a snap action electric switch, embodying the invention, with the switch cover removed; and

FIG. 2 is a perspective view, to a greatly enlarged scale, of the components of the switching system shown in FIG. 1.

DESCRIPTION OF THE PREFERRED EMBODIMENT

Referring to FIG. 1 of the drawing, a snap action electric switch embodying the invention is illustrated as comprising a housing 1 having extending, through the walls thereof, electrically conductive leads 2, 3 and 4 and serving to connect the switch into a circuit to be controlled. The ends of the leads 2 and 3 within housing 1 carry contact rivets 6 and 7 which cooperate with a movable contact 8. Contact 8 is secured to a rigid contact arm 9 near the free end of the latter, and the opposite end of contact arm 9 has pivotal bearing engagement in one arm of an L-shaped intermediate lever 10 of electrically conductive material. Lever 10, in turn, is pivotally mounted, intermediate its ends, on an electrically conductive bearing or fulcrum 4 forming part of the lead 4. Contact arm 9 and intermediate lever 10 are maintained in bearing engagement with their respective bearing points by the bias of a tension spring 11. For this purpose, tension spring 11 is connected to a first point on contact arm 9 and to a second, and fixed, point 13 on housing 1. Between its two suspension points, tension spring 11 is engaged with abutment means 12 mounted on that arm of intermediate lever 10 extending toward fixed spring suspension point 13. An actuating member or switch button 14 is displaceably mounted in housing 1 and engages that arm of lever 10 which extends toward contact arm 9, member or button 14 transmitting mechanical forces to intermediate lever 10.

As best seen in FIG. 2, the bearing or base end of contact arm 8 is forked, and the arm of lever 10 providing a bearing for contact arm 9 is also forked. Thereby, tension spring 11 connected to contact arm 9 and to fixed point 13 can move freely. Spring 11 is deflected away from the straight line interconnecting its two suspension points by means of abutment

means 12, which latter includes a lower abutment surface 12' underlying spring 11 and an upper abutment surface 12''' extending substantially parallel to surface 12' and overlying spring 11.

With the arrangement thus described, if an inwardly directed force acts on actuating member or button 14, member 14 is displaced inwardly of housing 1 and, in turn, displaces or adjusts intermediate lever 10. Lever 10 is thereby pivoted clockwise, as viewed in FIG. 1, with the bearing point thereon of contact arm 9 moving downwardly, also as viewed in FIG. 1. At the same time, abutment means 12 moves upwardly so that its abutment surface 12' engages and lifts the intermediate portion of spring 11. Due to this bilateral action, the angle of inclination of tension spring 11 relative to contact arm 9 changes relatively rapidly in the sense of accelerating the overcoming of the dead center of contact arm 9. As soon as the dead center position is overcome, movable contact 8 snaps out of engagement with counter contact or rest contact 7, with which it is normally engaged, and snaps into engagement with reversing contact 6. In the rest position of contact 8 in engagement with contact 7, the switch interconnects leads 3 and 4. After the switching of contact arm 9, by actuation of actuating member or button 14, the switch establishes an electrical connection between leads 2 and 4 and, upon release of the force from actuating member or button 14, the switching system automatically returns to the rest position shown in FIG. 1.

Tension spring 11 acts on intermediate lever 10 at two different points. On the one hand, contact arm 9 bears against a bearing point of lever 10 and, on the other hand, a force transversely of the axis of spring 11 is transmitted to spring 11 through abutment means 12.

These two forces produce opposite moments or torques on intermediate lever 10, with the magnitudes of the forces being so matched that there is a resulting counterclockwise moment effective on intermediate lever 11 in all possible positions of the latter. By selection of another fixed suspension point 15, 16 or 17, for anchoring the fixed end of spring 11, the actuating force necessary to be applied to actuating member or button 14 can be varied within wide limits without appreciable change in the contact pressure. If, for example, spring 11 has a fixed suspension point at the fixed point 15, only a small actuating force need be applied to actuating member or button 14. This is an important advantage of the present invention in that, in known arrangements, the required actuating force can be reduced only with the use of weaker springs and at the expense of the contact pressure. Anchoring of the fixed end of spring 11 to any fixed point other than point 15, such as at the fixed points 13, 16, or 17, results in an increase of the force required to actuate the switch. The resulting moment on intermediate lever 10 may be the result of either subtraction or addition of the two operative partial moments.

It will be understood by those skilled in the art that the particular abutment means 12 illustrated in the drawings may be replaced by an abutment engageable with only one side of spring 11, unless the construction is such that the force exerted on abutment means 12 changes direction within the range of pivotal movement of intermediate lever 10.

While a specific embodiment of the invention has been shown and described in detail to illustrate the application of the principles of the invention, it will be understood that the invention may be embodied otherwise without departing from such principles.

I claim:

1. A snap action electric switch comprising, in combination,

a housing; a pair of stops in spaced relation in said housing; a switch-actuating member displaceably mounted in said housing; a two-arm lever pivotally mounted, intermediate its ends, at a fulcrum in said housing in operative relation with said actuating member for adjustment as a function of displacement of the latter; a contact arm in said housing having one end bearing pivotally on a first arm of said lever and its other and free end movable between said stops; a tension spring having one end connected to a first suspension point on said contact arm spaced from its bearing end, extending substantially parallel to said lever in substantially central alignment therewith and in laterally spaced relation to said fulcrum, and having its opposite end connected to a second and fixed suspension point on said housing beyond said fulcrum, said spring biasing said contact arm into bearing engagement with said lever to exert a torque tending to pivot said lever in one angular direction about said fulcrum; and abutment means on the second arm of said lever extending toward said fixed point, said abutment means embracing said spring to act on opposite sides of the latter at a point beyond said fulcrum and intermediate the ends of said spring to deflect said spring, from a straight line connecting said first and second suspension points, in a direction to increase the tension of said spring acting on said lever, through said abutments means, to exert a torque tending to pivot said lever in the opposite angular direction about said fulcrum; said abutment means, upon pivoting of said lever by displacement of said actuating member, acting on said spring to deflect said spring in the opposite direction from the straight line connecting said first and second suspension points to snap said contact arm, by pivoting about its bearing end on said lever, from a rest position in which its free end engages one stop, to an actuated position, in which its free end engages the other stop, and to provide a restoring force acting to return said contact arm to its rest position; the line of action of said tension spring remaining in spaced relation to the same side of said fulcrum and out of engagement with said fulcrum in all positions of said switch.

2. A snap action electric switch, as claimed in claim 1, in which the arm of said lever providing a bearing for said contact arm is substantially L-shaped, the contact arm bearing on that leg of the L-shape which extends substantially normal to the general longitudinal extent of said lever.

3. A snap action electric switch, as claimed in claim 2, in which that end of said contact arm bearing on said lever is forked, and the leg of the L-shaped arm of said lever, on which said contact arm has bearing engagement, is also forked; said spring extending between the arms of the two forks for free movement of said spring.

4. A snap action electric switch, as claimed in claim 1, in which each of said stops is a respective electric contact connected to an external circuit, and a movable contact on the free end of said contact arm is engaged, in the rest position of said contact arm, with one of said first-mentioned contacts; and an external lead electrically connected to said movable contact.

5. A snap action electric switch, as claimed in claim 1, including a plurality of fixed suspension points for said spring in said housing; said suspension points being arranged in a row extending parallel to the direction of movement of said abutment means and being in spaced relation along said row; said opposite end of said tension spring being selectively connectable to a selected one of said fixed suspension points to selectively adjust the force required to displace said actuating member.
